UNITED STATES PATENT OFFICE.

WAITMAN D. CORDER, OF PHILIPPI, WEST VIRGINIA.

SUSPENDERS.

No. 914,021.

Specification of Letters Patent.

Patented March 2, 1909.

Application filed October 26, 1908. Serial No. 459,459.

To all whom it may concern:

Be it known that I, WAITMAN D. CORDER, a citizen of the United States of America, and resident of Philippi, county of Barbour, and State of West Virginia, have invented certain new and useful Improvements in Suspenders, of which the following is a specification.

This invention relates to new and useful 10 improvements in suspenders, and has for its primary object to provide suspenders having a simple, strong and durable back-construction which gives to the wearer an increased freedom of movement and greater ease and 15 comfort.

Further objects of the invention are to provide a suspender wherein a flexible connection is had between the shoulder-straps at the back; to provide a suspender in which 20 the shoulder-straps and back-straps are formed of separate pieces of material which are joined in such a manner that each strap is held in its proper angle; to provide a suspender the opposite sides of which may be 25 folded one upon the other in perfectly flat registering relation for facilitating the handling and packaging thereof; and to provide a suspender wherein the shoulder-straps and back-straps are connected by leather facings 30 and wherein there is a minimum of webbing inclosed by said facings for the reception and holding of leather-rotting moisture, and also wherein the facings are provided with perforations or air-openings whereby access of air 35 is had to the open space between said facings.

With these and other objects in view, the invention finally consists in the particular construction, arrangement and combination of parts which will hereinafter be described, 40 reference being had to the accompanying drawing, forming a part of this specification, in which—

Figure 1 is an elevation of a pair of suspenders embodying the present invention; 45 Fig. 2 is an elevation of the back-portion of the suspenders, showing the two sides thereof folded together; and Fig. 3 is an enlarged view of said back-portion, partly in elevation and partly in section.

Referring to said drawing, in which like 50 reference-numerals designate like parts throughout the several views—1 indicates a shoulder-web, 2 a back-strap, and 3 a transversely-directed loop, all formed of 55 separate pieces of elastic webbing material

and connected by a pair of oppositely-disposed facings 4, preferably made of leather, but which may be of any other appropriate material. The adjacent ends of a shoulder-web and its corresponding back-strap are 60 separated a distance exceeding the width of the web which forms the loop 3, and are stitched between the opposite ends of said facings 4, thus forming an open or unoccupied space between the facings into each of which 65 extends the ends of the webbing composing said loop. A lateral extension 4^a carried by each of the facings 4 is stitched to the body of the loop 3, as shown, an increased stitching area being thus provided which admits 70 of said open space being left unoccupied. For admitting of a circulation of air throughout said open space, a plurality of openings or perforations 5 are provided in the facings, as shown. The two oppositely disposed 75 loops 3 of the suspenders are connected by a metal link 6, as shown. Owing to the limited area of the shoulder-web and of the back-strap inclosed by said facings, a minimum of webbing is held in position for absorbing moisture, and consequently the 80 tendency to rot the stitches and the facings is greatly reduced.

On account of the elastic character of the webbing of which the loops 3 are formed, a 85 freedom of movement is permitted which is lacking in many suspender-back constructions.

Having thus described my invention, what I claim as new, and desire to secure by 90 Letters Patent, is—

1. In a suspender, shoulder-webs, back-straps, oppositely-disposed non-elastic facings connecting each web to the corresponding strap, the adjacent ends of said web and 95 strap being spaced apart to leave an unoccupied space between said facings, lateral extensions integral with said facings, a loop of elastic material having its ends held between said facings, and a link connecting 100 the opposite loops.

2. In a suspender, shoulder-webs, back-straps, oppositely-disposed non-elastic facings connecting each web to the corresponding strap, the adjacent ends of said web and 105 strap being spaced apart to leave an unoccupied space between said facings, said facings being provided with perforations which communicate with the unoccupied space, lateral extensions integral with said facings, 110

a loop of elastic material having its ends held between said extensions, and a link connecting the opposite loops.

3. Suspenders comprising shoulder-webs, 5 back - straps, oppositely - disposed leather- facings connecting each web to the corresponding strap so as to leave an unoccupied space between the adjacent ends of said web and strap, a loop of elastic material having 10 its ends secured between said facings, the said ends of the loop partially occupying the

unoccupied space between the ends of said web and strap, the facings having perforations therein in communication with the unoccupied space therebetween, and a link 15 connecting the opposite loops.

In testimony whereof I affix my signature in presence of two subscribing witnesses.

WAITMAN D. CORDER.
